(57) **CLAIM**

The ornamental design for a mobile computer, as shown and described.

DESCRIPTION

FIG. 1 is a perspective view of the top side of a mobile computer;

FIG. 2 is a perspective view of the bottom side of the mobile computer shown in FIG. 1;

FIG. 3 is another perspective view of the bottom side of the mobile computer shown in FIG. 1;

FIG. 4 is a front view of the mobile computer shown in FIG. 1;

FIG. 5 is rear view of the mobile computer shown in FIG. 1;

FIG. 6 is a bottom side view of the mobile computer shown in FIG. 1;

FIG. 7 is a top side view of the mobile computer shown in FIG. 1;

FIG. 8 is a left side view of the mobile computer shown in FIG. 1; and,

FIG. 9 is a right side view of the mobile computer shown in FIG. 1.

The broken line showing of unclaimed portions of the mobile computer forms no part of the claimed design.
